UNITED STATES PATENT OFFICE.

GEORGE W. CONNOR, OF BEAR WALLOW, NORTH CAROLINA.

WASHING APPARATUS.

1,183,724.

Specification of Letters Patent. Patented May 16, 1916.

Application filed August 12, 1913. Serial No. 784,373.

To all whom it may concern:

Be it known that I, GEORGE W. CONNOR, a citizen of the United States, residing at Bear Wallow, in the county of Henderson and State of North Carolina, have invented new and useful Improvements in Washing Apparatus, of which the following is a specification.

The invention relates to a washing apparatus, and more particularly to improvements in the type of machine construction set forth in Letters Patent No. 1,034,206, issued to me July 30, 1912.

The primary object of the invention is the provision of an apparatus of this character wherein the circulation of fluid serves to impart rotary motion to a clothes receiving cylinder so that the fluid will permeate clothes contained therein for the thorough washing 20 thereof and also the bleaching of the same.

Another object of the invention is the provision of an apparatus of this character wherein the circulating fluid is utilized for impelling a washing cylinder which is 25 driven under the action of the fluid, the motion of the cylinder may be imparted to machinery or other parts for operating the same.

A further object of the invention is the 30 provision of an apparatus of this character wherein a filtering medium is disposed in the circulating path of the fluid to collect from the water the dirt or any foreign matter and thereby prevent such matter from 35 affecting the clothes while being thoroughly cleaned during the operation of the apparatus, the fluid when again entering the cylinder containing the clothes being thoroughly filtered to free the same from dirt 40 and foreign matter.

A still further object of the invention is the provision of an apparatus of this character wherein a fluid turbine is operated under the action of the circulating fluid which is 45 also directed into a clothes washing cylinder for the cleansing of the clothes therein and the bleaching of the same, the turbine being designed especially for imparting rotation to machinery or the like for the driving of 50 the same.

A still further object of the invention is the provision of an apparatus of this character which is of novel form and which can be utilized for imparting power to machinery 55 or the like and also which may be utilized for the washing and bleaching of clothes.

A still further object of the invention is the provision of an apparatus of this character which is extremely simple in construction, reliable and efficient in operation, and 60 inexpensive in manufacture.

With these and other objects in view, the invention consists in the construction, combination and arrangement of parts as will be hereinafter fully described, illustrated in 65 the accompanying drawing, and pointed out in the claims hereunto appended.

In the drawings:—Figure 1 is a vertical longitudinal sectional view through an apparatus constructed in accordance with the 70 invention. Fig. 2 is a sectional view on the line 2—2 of Fig. 1. Fig. 3 is a sectional view on the line 3—3 of Fig. 1. Fig. 4 is a sectional view on the line 4—4 of Fig. 1. Fig. 5 is a sectional view through the turbine 75 casing of the apparatus.

Similar reference characters indicate corresponding parts throughout the several views in the drawings.

Referring to the drawings in detail, the 80 apparatus comprises a receptacle or tank A having beneath its main bottom 5 a combustion chamber 6, the forward end of which communicates with a fire box 7, while its rear end communicates with a discharge 85 flue 8, the walls 9 of the said chamber 6 being suitably fixed to the receptacle or tank A to form a unitary structure. Provided in the front wall of the fire box 7 is a suitable doorway 10 whereby fuel can be introduced into 90 the said firebox, the doorway being closed by means of a door 11 which is mounted on the front wall of the fire box in any desirable manner. The main bottom 5 of the receptacle or tank A near its front end is formed 95 with a depending portion providing a trough 12, while journaled for rotation internally of the receptacle or tank A is a clothes receiving cylinder 13 formed at its periphery with buckets 14, the same being spaced 100 apart to provide slots 15 therebetween, the axle 16 of the said cylinder 13 being journaled in the side walls of the receptacle or tank. Arranged above the main bottom 5 of the receptacle or tank is a supplemental bottom 17, these bottoms being spaced apart to 105 form an intervening lower circulating chamber 18 which is adapted to direct a current of fluid to the cylinder 13, one end of the supplemental bottom 17 being formed with a down-turned flange 19 at right angles thereto which projects into the trough 12,

while its opposite end is formed with an upwardly curved guide extension 20 adapted to direct the current of fluid in the direction of the buckets 14 on the cylinder 13 so that 5 the impact of the fluid will rotate the latter during the operation of the apparatus.

Arranged within the receptacle or tank A is a vertical partition 21, the lower end of which terminates spaced from the supplemental bottom 17, while its upper end is 10 united to the top 22 of the said receptacle or tank, the partition being formed with a series of openings 23 adapted to be controlled by means of a gate 24 which is formed with 15 openings 25 adapted to register with the openings 23, and in this manner the fluid discharged from the buckets will be controlled so as to reduce or increase the speed of rotation of the cylinder 13 as will be clearly 20 apparent.

Spaced from the curved extension 20 of the supplemental bottom is a deflector plate 26 which serves to direct the current of fluid to the buckets from the chamber 18.

25 Tapped or otherwise secured in the inner vertical walls of the trough 12 is a pair of spaced parallel fluid feed tubes 27, the inner ends of which are formed with up-turned injector nozzles 28 which extend upwardly 30 through the main bottom 5 of the receptacle or tank A and are positioned in the space between the extension 20 and the plate 26 so that fluid passing into the tubes 27 will be delivered in a jet to the buckets 14 for impelling the cylinder 13, which is formed with a hinged door 29 so that access may be had thereto for the introduction of clothes therein or the removal of the said clothes therefrom.

35 Arranged within the fire box 7 is a water heating coil 30, the same serving as a grate for the fuel and also extends into the combustion chamber 6, the portion of the coil extended within the latter being superimposed upon the tubes 27, one end of the coil being connected to a coupling 31 which is tapped into the end wall of the trough 12 so that fluid therein will be admitted to the coil 30. The opposite end of the coil 30 is 40 suitably fastened to a casing 32 which is fixed exteriorly to the receptacle or tank A and has arranged therein the respective intermediate turbine wheel 33 and the turbine wheels 34, which latter are disposed at 45 opposite sides of the wheel 33, one wheel 34 being fixed to the axle 16 of the cylinder 13, and the other to the said cylinder so as to rotate in unison, while the wheel 33 is held stationary within the casing 32 in any suitable manner.

50 The wheels 33 and 34 are formed with peripheral impact blades or vanes 35 so that fluid delivered into the casing 32 from the coil 30 will act directly upon the vanes 35 55 for the driving of the wheels 34, thereby as-

sisting in the rotation of the cylinder 13, the axle carrying one of the wheels 34 being extended exteriorly of the casing 32 and has fitted thereon belt wheels 36 so that on the use of a belt, (not shown), motion from the cylinder can be imparted to machinery or the like for the driving of the same.

On rotation of the cylinder 13 the buckets 14 when filled with water serve to rotate the same so that the weight of the fluid therein aids in the rotation of the said cylinder for a portion of each revolution thereof.

60 In the top 22 of the receptacle or tank A is formed a filling opening 37 which is provided with a removable cover 38 so that through this opening fluid can be introduced into the receptacle or tank. Arranged in the forward end portion of the receptacle or tank A is a rearwardly inclined reticulated filtering element 39 which is disposed in the 65 circulating course of the fluid and the said element extends entirely across the receptacle or tank so that it will remove all dirt and foreign matter from the fluid after it has passed through the cylinder 13 for the 70 cleaning of the clothes held therein during the working of the apparatus. Thus it will be seen that the filtered fluid will be again conducted through the coil 30 and tubes 27 to the cylinder and also the filtered fluid 75 will pass through the circulating space or chamber 18 to the said cylinder. The front wall 40 of the receptacle or tank A extends downwardly and forwardly and merges into the front wall of the trough 12, and by reason of this construction the fluid will be prevented from splashing upwardly and outwardly through the open portion 41 and the top of the receptacle or tank, the current of the fluid being directed downwardly into 80 the trough when contacting with the front wall of the said receptacle or tank. The end of the cylinder 13 contiguous to the turbine wheel 34 is formed with a series of openings 42 which permits the inflow of fluid 85 therethrough into the cylinder after its impact against the vanes 35 on the said wheel 34. The wall of the receptacle or tank A throughout the area of the casing 32 is cut away so as not to interfere with the flow of 90 the fluid from the turbine wheels 33 and 34 in the direction of the cylinder.

95 The inner end of the combustion chamber 6 connecting it with the flue 8 is contracted at 43 so that the products of combustion are 100 thoroughly utilized for the heating of the tubes 27, the coil 30 and the receptacle or tank A before the products of combustion are dispensed into the flue, and by reason of this contracted portion 43 the discharge of 105 smoke from the combustion chamber 6 is reduced to a minimum.

110 In the operation of the apparatus water is introduced into the receptacle or tank A to a predetermined level therein, and there- 115

after fuel is placed within the fire box 7 and ignited. The products of combustion from the fuel will play upon the coil 30, the tubes 27 and the receptacle or tank A, and when 5 the water reaches the boiling point the same will be agitated, thereby setting up currents, these currents being directed through the chamber 18, tubes 27 and coil 20 so that the fluid will act upon the cylinder 13 and the 10 vanes of the turbine wheels 33 and 34, thereby rotating the said wheels 34 for drawing the said cylinder. The water while circulating will penetrate the clothes within the cylinder 13 for the thorough washing and 15 bleaching of the same, and on the rotation of the turbine wheel 34 the power therefrom can be utilized for driving machinery or the like. When operating the gate 24 the circulating water can be retarded or let out 20 more freely, thus controlling the rotation of the cylinder 13 for decreasing or increasing the speed of rotation thereof.

From the foregoing it is thought that the construction and manner of operation of 25 the device will be clearly understood, and therefore a more extended explanation has been omitted.

What is claimed is:—

1. A washing machine comprising a receptacle having a depending portion providing a trough near one end, a clothes receiving cylinder rotatably journaled within said receptacle and having peripheral buckets spaced from each other to provide slots 30 therebetween, each bucket being formed with an outer wall angularly disposed and an inner outwardly ribbed portion spaced from said wall to provide a pocket, a supplemental bottom arranged parallel with and 35 spaced above the main bottom of the receptacle, a downturned portion formed at one end of the supplemental bottom and extended within the trough, an upwardly curved portion formed at the opposite end 40 of the supplemental bottom, a vertical partition located within the receptacle and terminating spaced from the supplemental bottom, a deflector plate within the receptacle 45 spaced from the upwardly curved end of the supplemental bottom, and arched correspondingly to the periphery of the cylinder, a rearwardly inclined reticulated filtering element extending from one end to the supplemental bottom to be located between said end and the partition, and means for ejecting 50 fluid from the trough to the buckets at a point between the supplemental bottom and the deflector plate.
2. A washing machine comprising a receptacle having a depending portion providing a trough near one end, a clothes receiving cylinder rotatably journaled within said receptacle and having peripheral buckets spaced from each other to provide slots 55 therebetween, each bucket being formed with an outer wall angularly disposed and an inner outwardly ribbed portion spaced from said wall to provide a pocket, a supplemental bottom arranged parallel with and spaced above the main bottom of the receptacle, a 60 downturned portion formed at one end of the supplemental bottom and extended within the trough, an upwardly curved portion formed at the opposite end of the supplemental bottom, a vertical partition located within the receptacle and terminating 65 spaced from the supplemental bottom, a deflector plate within the receptacle spaced from the upwardly curved end of the supplemental bottom, and arched correspondingly to the periphery of the cylinder, a rearwardly inclined reticulated filtering element extending from one end to the supplemental bottom to be located between said end and the partition, means for ejecting 70 fluid from the trough to the buckets at a point between the supplemental bottom and the deflector plate, the said partition being formed with a plurality of perforations, and a gate slidably supported on the partition 75 for controlling the perforations.

In testimony whereof I affix my signature in presence of two witnesses.

GEORGE W. CONNOR.
